**REVERSING SWITCH FOR TAP CHANGING
TRANSFORMER REGULATOR**

Piero B. Macelloni, Pittsfield, Mass., assignor to General Electric Company, a corporation of New York

Filed Apr. 12, 1962, Ser. No. 187,062

5 Claims. (Cl. 200—170)

This invention relates to electric switches and more particularly to improvements in reversing switches for use in tap changing type transformer regulators.

Heretofore switches of this type have had considerable friction and they have caused undue strain on and in some cases actual stalling of the operating mechanism of the regulator.

In accordance with this invention there is provided a novel and simple switch which assures very firm eventual contact engagement when moved in either direction from a neutral position in which there is practically no initial friction and reduced final friction with the friction during the initial contact engagement occurring at a location where the opposing moment arms are small so as to provide a large mechanical advantage during this period of operation of the switch.

An object of the invention is to provide a new and improved electric switch.

Another object of the invention is to provide a new and improved reversing switch for tap changing type transformer regulators.

The invention will be better understood from the following description taken in connection with the accompanying drawing and its scope will be pointed out in the appended claims.

In the drawing, FIG. 1 is a perspective view of a preferred embodiment of the invention and FIG. 2 is an elementary circuit diagram of how it may be connected to a transformer tap changing type regulator.

Referring now to the drawing and more particularly to FIG. 1, there is shown therein a contact 1 and a contact 2 spaced therefrom along the arc of a circle having its center on the axis 3 of a sector shaped common contact 4. Actually the sector shaped common contact 4 consists of a contact 5 and a contact 6 which may, if desired, be separate contacts but which are preferably shown permanently connected together. Cooperating with the four contacts 1, 2, 5, and 6 are a pair of bridging contact fingers 7. The contact 5 is generally radially aligned with the contact 1 and the contact 6 is generally radially aligned with the contact 2. Furthermore, it is immaterial whether the bridging contacts 7 are the movable contacts and the other contacts are the stationary contacts or vice versa, the only essential thing being that there be relative movement. However, I prefer the former arrangement in which the bridging contacts 7 are movable and the radially aligned contact pairs 1-5 and 2-6 are fixed contacts. It will be noted that the contacts 1, 2, 5 and 6 have a thickness "d" between flat sides and that they are all mounted in generally coplanar relation with their flat sides parallel to their common plane which is generally perpendicular to the common axis 3. It will also be noted that the angular displacement between the facing edges of the radially outermost fixed contacts 1 and 2 is less than the angular displacement between the facing edges of the radially innermost fixed contacts 5 and 6.

2

Furthermore, while all of those facing edges are somewhat chamfered or beveled, this is much more pronounced on the radially innermost fixed contacts 5 and 6 which preferably have rather sharp edged wedge-shaped facing edges.

5 The elongated bridging contact fingers 7 are carried by a frame 8 mounted for rotation in the sector 4 about the axis 3. This frame is shown as having a pair of parallel radially extending arms 9 between which extend a pair of parallel radially spaced tie rods 10 on which the contact fingers 7 are mounted by means of suitable holes located therein. Coiled compression springs 11 mounted on the rods 10 between the contact fingers 7 and the arms 9 serve to urge or bias the contact fingers 7 toward each other. 10 However, they are held apart by tubular spacers 12 and 13 mounted respectively on the rods 10 between the contact fingers 7. The spacer 12 is longer than the spacer 13 but shorter than the thickness of the contacts 1 and 2. Actually only one arm 9 is necessary, in which case the 15 springs 11 are retained on the outer ends of rods 10 in any suitable manner.

The switch is shown in FIG. 1 in its so-called neutral position in which the bridging contact fingers 7 are between the respective pairs of fixed contacts 1-5 and 2-6 20 but out of engagement therewith. If now the frame 8 is rotated in either direction from this neutral position, the first thing to be noted is that the radially outermost ends of the contact fingers 7 will come into overlying relation with opposite sides of either contact 1 or contact 2, depending on the direction of rotation of the frame, 25 without touching them before any contact is made between the radially innermost ends of the contact fingers 7 and the radially innermost fixed contacts 5 and 6. This is illustrated by the clockwise rotated dashed line 30 position of fingers 7 and is because of the smaller angular distance between the facing edges of the contacts 1 and 2 than between the facing edges of the contacts 5 and 6. When the inner ends of the contact fingers 7 first contact either the fixed contact 5 or the fixed contact 6 there will 35 be a wedging action caused by the pronounced wedge shape of the facing edge of the contact 5 or contact 6. At this point for the first time there will be introduced noticeable reactive impact and frictional forces opposing the rotation of the frame 8. However, because these 40 forces are located near the axis 3 their moment arms will be comparatively small and they thus will not have a pronounced restraining effect on the continuing rotary movement of the frame 8. As this rotary motion continues the wedging action will spread the radially inner 45 ends of the contact fingers 7, which will pivot about points 14 where the ends of the spacer 12 touch the contact fingers 7. This will, of course, move the outer ends of the contact fingers toward the sides of the contacts 1 or 2 as the case may be. As this action continues the 50 outer ends of the contact fingers 7 will engage the sides of the contact 1 or the contact 2 as the case may be and with still further rotary movement the pivot points of the fingers 7 will now be moved further outwardly to the 55 points of contact between fingers 7 and the sides of contacts 1 or contact 2 as the case may be so that when the frame 8 reaches the limit of its travel in either direction the full force of the compression springs 11 will be exerted to pinch the contact pairs 1-5 or 2-6 between the contact fingers 7. This in turn is because the length of the 60 spacer 12 is less than the thickness of the contacts 1 and 2. 65

This position is illustrated by the counter-clockwise rotated dashed line position of the fingers 7.

FIG. 2 shows how the switch may be connected as a reversing switch for a multitap series winding 15 of an autotransformer type voltage regulator 16. As shown the series winding 15 is provided with a tap changing ratio adjuster switch 17 while contacts 1 and 2 of the reversing switch are connected to the terminals of the series winding 15 and the common contact 4 of the reversing switch is connected to one of the lines of the circuit for the regulator 16. In general, the purpose of the reversing switch is to double the range of regulation of the regulator 16 by causing the series winding to be connected for one polarity of the series winding 15 throughout the complete range of the operation of the tap changer 17 while in the other position of the reversing switch the polarity of the series winding 15 is reversed so that the tap changer 17 may go through its complete range of operation, again thus providing selective voltage raising and lowering or voltage buck and boost action as the tap changer 17 goes through its range of operation.

While there has been shown and described a particular embodiment of the invention, it will be obvious to those skilled in the art that changes and modifications may be made without departing from the invention, and therefore it is intended by the appended claims to cover all such changes and modifications as fall within the true spirit and scope of the invention.

What I claim as new and desire to secure by Letters Patent of the United States is:

1. In an electric switch a pair of spaced apart contacts, a bridging contact, means for causing relative movement in a given plane between said bridging contact and said pair of contacts for causing selective bridging engagement and disengagement between said bridging contact and said pair of contacts, means mounting said bridging contact to cause engagement of said bridging contact first with only one of said pair of contacts with said bridge contact and the other of said pair of contacts being in spaced apart overlying relation and means cooperating with said mounting means for causing relative movement between said bridging contact and said pair of contacts in a plane perpendicular to said given plane for next causing said bridging contact to engage said other of said pair of contacts.

2. In an electric switch, a pair of coplanar flat sided spaced apart contacts, a bridging contact, means for causing relative rotary movement in a given plane about a common axis between said bridging contact and said pair of flat sided contacts for causing selective bridging engagement and disengagement between said bridging contact and the sides of said pair of contacts, means mounting said bridging contact to cause engagement of said bridging contact first with a radially innermost one only of said pair of contacts with said bridging contact and the radially outermost other of said pair of contacts in spaced apart overlying relation, and means cooperating with said mounting means for causing relative movement between said bridging contact and said pair of contacts in a plane perpendicular to said given plane for next causing said bridging contact to engage a side of the radially outermost of said pair of contacts.

3. In an electric switch, four generally flat sided contacts mounted in coplanar relationship, said contacts being grouped in two pairs aligned along different radii from a common center, the radial location of the contacts of each pair being the same, a pair of elongated bridging contacts extending in a radial direction from said common center means for moving said bridging contacts around said common center from a position in which they respectively bridgely engage opposite faces of one pair of flat sided contacts through a neutral position in which they are out of contact with said flat sided contacts to a position where they respectively contact op-

posite faces of other pair of flat sided contacts, means for biasing said bridging contacts toward each other for causing their opposite ends to pinch each pair of flat sided contacts, and spacer means between said bridging contacts for causing their ends nearest said common center to be closer together than the thickness of the two radially innermost flat sided contacts and their ends farthest from said common center to be farther apart than the thickness of the two radially outermost flat sided contacts when said bridging contacts are in said neutral position, the angular separation of the facing edges of the radially outermost flat sided contacts being less than the angular separation of the facing edges of the radially innermost contacts whereby when said bridging contacts are moved from said neutral position their outer ends are spaced from but overlie the radially outermost flat sided contacts when their inner ends first contact the edges of the radially innermost flat sided contacts, said edges of said radially innermost flat sided contacts being wedge shaped for entering between the inner edge of said bridging contacts so as to cause the outer ends of said bridging contacts to move toward each other and pinch the radially outermost contacts therebetween.

4. In an electric switch, four generally flat sided fixed contacts of generally equal thickness mounted in a spaced relation with their flat sides in parallel coplanar relation, said fixed contacts being grouped in two pairs in which each pair is aligned along different radii from a common center, the radial location of the contacts of each pair along their respective radii being the same, a pair of elongated flat sided bridging contacts extending in a radial direction from said common center, means for moving said bridging contacts in union around a common center in a position in which their flat sides respectively bridgely contact opposite faces of one pair of flat sided fixed contacts through a neutral position in which they are out of contact with said flat sides fixed contacts to a position where they respectively bridgely contact opposite faces of the other pair of flat sided fixed contacts, spring means for biasing said bridging contacts toward each other for causing their opposite ends to pinch each pair of flat sided contacts and spacer means between said bridging contacts for causing their ends nearest said common center to be closer together than the thickness of the two radially innermost flat sided fixed contacts and their ends farthest from said common center to be farther apart than the thickness of the two radially outermost flat sided fixed contacts when said bridging contacts are in said neutral position, the angular separation of the facing edges of the radially outermost flat sided fixed contacts being less than the angular separation of the facing edges of the radially innermost fixed contacts whereby when said bridging contacts are moved from said neutral position their outer ends are spaced from but overlie the radially outermost flat sided fixed contacts when their inner ends first contact the edges of the radially innermost flat sided fixed contacts, said edges of said radially innermost flat sided fixed contacts being wedge shaped for entering between the inner ends of said bridging contacts and spreading them apart so as to cause the outer ends of said bridging contacts to move toward each other and pinch the radially outermost fixed contacts therebetween.

5. An electric switch comprising, in combination, a frame mounted for rotation about a fixed axis through equal angles from a neutral position, two pairs of fixed contacts, each pair of fixed contacts being aligned respectively on different radii from a point on said axis which radii having angular displacement equal to the range of angular motion of said frame, the radially outermost contacts of each pair of fixed contacts having the same radial distance from said axis and the radially innermost contacts of each pair of fixed contacts having the same radial distance from said axis, said frame having a pair of axially spaced arms extending radially from said axis in the same direction, a pair of parallel radially spaced

tie rods joining said arms and so located as to pass between the contacts of each pair of fixed contacts when said frame is rotated through said angles from its neutral position, a pair of bridging contact fingers loosely mounted on said rods, coiled compression springs on said rods between said arms and said contact fingers, and a pair of tubular spacers on said rods between said contact fingers, the spacer on the radially outermost rod being longer than the other spacer but shorter than the axial distance between opposite sides of said fixed contacts, the edges 10 of the radially innermost of said pairs of fixed contacts

being beveled in a direction facing the inner ends of said bridging contact fingers.
